Anton Dietrich, Munich, Germany, assignor to Optische Werke G. Rodenstock, Munich, Germany, a company of Germany

Filed Oct. 20, 1965, Ser. No. 87,615

Term of patent 14 years

(Cl. D57—1)

FIG. 1 is a perspective side view of an eyeglass frame showing my new design;

FIG. 2 is a top perspective view thereof;

FIG. 3 is a rear elevational view thereof, showing one temple in folded position;

FIG. 4 is a cross-sectional view taken on the line 4—4 of FIG. 2; and

FIG. 5 is a cross-sectional view taken on the line 5—5 of FIG. 2.

The dominant features of my design reside in the portions shown in full lines.

I claim:

The ornamental design for an eyeglass frame, substantially as shown and described.
